UNITED STATES PATENT OFFICE.

WILLIAM J. PATTERSON AND ROSS M. BICKLEY, OF PITTSBURGH, PENNSYLVANIA,
ASSIGNORS TO HEYL & PATTERSON, INC., OF PITTSBURGH, PENNSYLVANIA, A COR-
PORATION OF PENNSYLVANIA.

COAL-CLEANING APPARATUS.

1,312,867.

Specification of Letters Patent. Patented Aug. 12, 1919.

Application filed March 5, 1919. Serial No. 280,854.

To all whom it may concern:

Be it known that we, WILLIAM J. PATTERSON and Ross M. BICKLEY, citizens of the United States, and residents of Pittsburgh, 5 in the county of Allegheny and State of Pennsylvania, have invented a new and useful Improvement in Coal-Cleaning Apparatus; and we do hereby declare the following to be a full, clear, and exact description 10 thereof.

Our invention relates to apparatus for cleaning coal.

The purpose of the invention is to provide means for keeping track of the quality of 15 the coal that is being loaded in the mines. It frequently happens that some mining cars contain an unusually high percentage of refuse such as stone or slate, due to carelessness of the miner in loading said cars. It 20 is necessary to call the miner's attention to this refuse so as to discourage the practice of sending out dirty coal. Where cars are hoisted from the mine to the tipple on self-dumping cages the identity of any partic- 25 ular car is lost as soon as it is dumped unless some provision is made for diverting the coal for inspection.

In the cleaning of coal it is found that the greater part of the easily removable impurities are found in the size larger than 30 one and one-quarter inch. By our invention provision is made therefore for screening the coal, for weighing the lump and slack coal together and delivering them together 35 to a bin or other receptacle, or for delivering the slack only to the bin and delivering the lump coal to the picking table, where it may be inspected by the miner or inspector. The refuse that is picked out may then be 40 weighed to determine what percentage the impurities were of the total weight of coal in the car. After the refuse has been picked out the coal may be delivered to the bin by reversing the direction of movement of the 45 picking table, said table being arranged in such proximity to the bin as to effect this result. If, however, all of the coal is considered bad it may be discharged into a refuse chute from the picking table.

In the accompanying drawing Figure 1 50 is a side elevation of our improved apparatus shown in connection with an ordinary tipple; Fig. 2 is a plan view; Fig. 3 is an enlarged sectional view of the weigh-hopper, the bin, and the chute for delivering the 55 lump coal to the picking table, a portion of which is shown, and Fig. 4 is a section on the line 4—4, Fig. 3.

In the drawing the numeral 2 designates a suitable tipple in which is located the shaft 60 3 provided with suitable hoisting mechanism to hoist the cages 4 which receive the cars 5. Suitable mechanism is provided for dumping the cages when they reach the dumping point and the mechanism illustrated is a 65 common form which forms no part of my present invention. Said mechanism comprises generally stated the curved guide 6 adapted to receive the rollers 7 on the cage, whereby the cage carrying the car is dumped 70 into the position indicated by dotted lines Fig. 1.

A chute 8 is located in position to receive the coal dumped from the car, and said chute delivers the coal to the weigh-hopper 9. 75 This weigh-hopper 9 is divided by the screen bars 10 into a top and bottom deck 11 and 12. Gates 13 and 14 are provided for the upper and lower decks 11 and 12 respectively, said gates being opened and closed by 80 means of the fluid-operated cylinder 15. The piston-rod 16 is connected to the bell-crank 17 and a rod 18 connects said bell-crank to the gate 13. Bars 19 and 20 are pivoted to the gate 13 and to the hopper 9, and a bar 21 is pivotally connected to the bar 20 and to the gate 14. By these connections the operation of the cylinder 15 acts to open and close the gates 13 and 14 simultaneously. 85

Under normal conditions the weigh-hopper 9 delivers the lump and slack contained therein to the chute 22 which delivers the coal to the storage bin 23.

In order to deliver the lump coal when 95 desired to the picking table 24, the chute 25 is provided which connects up with the upper deck 11 of the weigh-hopper 9, and

said chute 25 is provided with the opening 26 in its bottom controlled by the fly-gate 27, hinged at 29. This gate 27 is opened and closed by the fluid-operated cylinder 30, pis-
5 ton rod 31 of said cylinder being connected up by the arm 32 to said gate whereby said gate may be moved into position to close the opening 26 or may be raised to the position indicated in dotted line Fig. 3, where it
10 is desired to discharge the contents of the upper deck 11 into the chute 22.

The lower end of the chute 25 is also provided with a gate 33 hinged at 34 and raised and lowered by a cable 35. In this manner
15 provision is made for retaining the coal delivered to the chute 25 in said chute until it is desired to deliver it onto the picking-table 24.

The picking-table 24 may be of any suitable construction, that shown being of a common type consisting of an endless conveyer belt 24^a mounted on drums 24^b. Any suitable means may be provided for driving the belt 25 and for reversing its direction of movement.

An operating platform 40 is provided for the operator from which he is able to control the cylinders 15 and 30 by means of the levers 41 and 42 respectively.

30 The operation of our invention is as follows:

The cars of coal are hoisted on the cages in the shaft and on reaching the dumping point the cars are dumped and the contents
35 delivered into the weigh-hopper 9. The finer coal or slack will fall through the screen bars 10 onto the lower deck, while the larger or lump coal may remain in the upper deck 11. The coal is then weighed. If
40 the inspector from his position on the cage tender's platform sees that the coal is free or comparatively free from refuse, he signals the operator who by means of the lever 41 operates the cylinder 15 and through the
45 connections described opens the gates 13 and 14, the gate 27 having been raised to the position indicated in dotted lines Fig. 3. This permits the coal from both decks to pass into the chute 22 and into the bin 23.

50 If, however, the inspector believes that the coal in the upper deck 11 contains too great a percentage of refuse he signals the operator who moves the lever 42 and operates the cylinder 30 which lowers the gate
55 27 to close the opening 26 in the chute 25. He then moves the lever 41 to operate the cylinder 15 and the gates 13 and 14 are opened. The slack coal in the lower deck 12 passes as before down into the bin but
60 the lump coal is delivered into the chute 25 and is collected at the lower end thereof. The picking-table 24 is then put in operation and the coal is delivered by lifting the gate 33 to the picking-table, a sufficient

amount to distribute the coal properly over 65 the surface of said table. The picking table is then stopped and the pickers remove the refuse from the coal, leaving the cleaned coal on the picking table. The refuse so removed from the coal is then weighed to 70 determine what percentage the impurities are of the total weight of coal in the car.

The cleaned coal on the picking-table 24 may then be delivered into the bin 23 by reversing the travel of the belt 24^a. 75

What we claim is:

1. In apparatus for cleaning coal, the combination of a weigh-hopper, a screen dividing said hopper into an upper and lower deck, said upper and lower decks 80 having discharge openings, gates controlling said openings, means for operating said gates, a common chute to receive the contents of said upper and lower decks, a picking-table and means for diverting the 85 coal from the said upper deck to said picking-table.

2. In apparatus for cleaning coal, the combination of a weigh-hopper, a screen dividing said hopper into an upper and 90 lower deck, said upper and lower deck having discharge outlets, gates controlling said outlets, means for operating said gates, a chute in line with said upper deck, a common chute to receive the coal from said upper and lower decks, said first named chute having an opening communicating with said common chute, a gate for said opening, and a picking-table to receive the coal from said first named chute. 95

100 3. In apparatus for cleaning coal, the combination of a weigh-hopper, a screen dividing said weigh-hopper into upper and lower decks, said decks having discharge openings, gates controlling said openings, 105 a common chute to receive the coal from said decks, a traveling picking-table, and means for diverting the coal from said upper deck onto said picking-table.

4. In apparatus for cleaning coal, the 110 combination of a weigh-hopper, a screen dividing said hopper into upper and lower decks, said decks having discharge outlets, gates controlling said outlets, a common chute to receive the coal from said decks, 115 a bin, a traveling picking-table, and means for diverting the coal from said upper deck to said picking-table, said picking-table being in proximity to said bin whereby the coal on said table may be delivered to said 120 bin.

5. In apparatus for cleaning coal, the combination of a weigh-hopper, a screen dividing said hopper into upper and lower decks, said decks having discharge outlets, 125 a common chute to receive the coal from said decks, a chute in line with said upper deck, an opening in said chute communi-

cating with said first named chute, a gate
controlling said opening, a traveling pick-
ing-table at the lower end of said second
named chute, and a gate controlling the
5 flow of coal from said secodn named chute
to said picking-table.

In testimony whereof, we the said WIL-

LIAM J. PATTERSON and Ross M. BICKLEY
have hereunto set our hands.

WILLIAM J. PATTERSON.
ROSS M. BICKLEY.
